UNITED STATES PATENT OFFICE.

RONALD E. J. NORDQUIST, OF MAPLEWOOD, NEW JERSEY, ASSIGNOR TO AMERICAN CAN COMPANY, OF NEW YORK, N. Y., A CORPORATION OF NEW JERSEY.

COMPOUND LINING CAN ENDS.

Application filed February 2, 1927. Serial No. 165,398.

This invention relates to compound applying or lining machines for can ends, and has more particular reference to the provision of a compound applying or lining machine adapted interchangeably to successively and commercially apply lining compound to flanged can ends of both circular and non-circular contour.

In the manufacture of cans for various purposes, it is the custom to double seam the ends to the body. For this purpose the end of the can body is flanged outwardly and the can end is provided with a flange offset from the flange of the end by a shoulder which fits within the can body and the outer edge of the flange is curled. This construction of the end provides a channel at the flange, in which a gasket or lining material is customarily provided.

20 In the seaming operation, the flange of the body is inserted past the shoulder on the end and within the curl. The parts are then rolled together into tight relation. The lining material provided upon the flange of 25 the end is thus rolled into the seam as it is tightly compressed to provide a hermetic closure. The lining material is frequently applied in liquid or semi-liquid form as a compound which not infrequently contains 30 rubber. This compound is dried by air or in a suitable apparatus to solid form. The double seaming operation is a delicate one, and it is desirable that exactly the right amount of compound be applied evenly 35 throughout the entire can end flange length.

My invention contemplates the provision 40 of an apparatus for accurately applying lining compound to a can end flange, whatever the contour or shape of the end may be, and this through the provision of simple instrumentalities and devices adapted for certain accurate operation, and which are unlikely to require constant attention and/or frequent repair, replacement or readjustment of the parts.

45 Another important object of the invention is the provision of an apparatus of this character which may be readily converted from an arrangement accurately lining a can end into an arrangement to line an end of a wholly different shape.

Another important object of the invention 50 is the provision of a can end compound liner which will be fully automatic in its action and adapted with equal facility to be em-

ployed for the lining of circular, rectangular, and other non-circular ends through simple substitution of parts.

Another important object of the invention 60 is the provision of a can end compound lining apparatus wherein no compound will be applied or will be delivered from the lining nozzle unless a can end be present to receive the compound.

Another important object of the invention 65 is the provision of an apparatus for applying compound lining material to can ends wherein the lining material may be maintained at even predetermined temperature until it is delivered from the nozzle, thus 70 permitting the employment of compounds which will congeal or thicken in ordinary room temperatures.

Numerous other objects and advantages of 75 the invention will be apparent as it is better understood from the following description, which, taken in connection with the accompanying drawings, discloses a preferred embodiment thereof.

Referring to the drawings:

Figure 1 is a top plan view of an apparatus embodying my present invention;

Fig. 2 is a partial enlarged plan detail thereof, the parts being shown in section;

Fig. 3 is an enlarged side elevation of the 85 same showing an end feed;

Fig. 4 is a vertical section taken transversely of the apparatus at the lining station, and taken substantially on line 4-4 of Fig. 1;

Fig. 5 is a vertical section taken through the nozzle support and showing the nozzle organization taken substantially on the line 5-5 of Fig. 1;

Fig. 6 is a longitudinal horizontal section 95 through a portion of the driving mechanism;

Fig. 7 is a section taken substantially on the line 7-7 of Fig. 4;

Fig. 8 is an enlarged detail showing a portion of the "no can no compound" feed construction; and

Figs. 9 to 12 are details of the Geneva movement for controlling the rotation of the 105 presented can end.

The embodiment of my invention shown on the drawings contemplates the feeding of can ends either automatically or by hand to a lining station, where the end is lifted by a support to enter clamping engagement with 110

a clamp arranged thereabove. After the end is lifted, it is rotated throughout more than a complete rotation, and preferably throughout a rotation and a half, this being for the purpose of giving time to accurately start and stop the delivery of the compound.

The compound is delivered by a nozzle which is arranged above the flange of the end. A valve is opened after the end has started to rotate and is closed before it finishes. Preferably, this valve remains open merely long enough to give the smallest possible overlap to the applied compound on the flange. The nozzle is mounted upon an arm that swings about an axis remote from the nozzle, the nozzle being capable, therefore, of moving from and toward the axis of the rotation of the end.

A cam is mounted in the present embodiment of the invention beneath the can end, and this cam is provided with a groove of exactly the shape of the end. A cam roller engages in the groove and is arranged upon the end of an arm adapted to move with the nozzle; i. e. to cause the movement of the nozzle in accordance with the shape of the flange on the end.

A tank for the compound is provided, and the delivery conduits between the tank and the nozzle are all heat-jacketed; or at any rate, provided with jackets adapted to contain a heating medium, so that when desired the compound may be delivered to the flange at predetermined temperature. The construction and arrangement of the parts is such that merely by changing the construction and period of nozzle opening, the apparatus may be arranged to accurately deliver compound lining material to the flanged can ends of different configuration.

Referring to the drawings:

Reference character 21 indicates a suitable bed or table construction supported in any usual or preferred manner by a base framework 22.

Reference character 23 indicates the can end support located at the lining station. Two can end guides 24 are arranged to lead to and past this lining station and between them a feed support 25 is or may be arranged. Two can end feed slides 26 are arranged between the guides 24, one moving closely adjacent each guide member. The feed slides 26 are connected by a crosshead 27, which in turn is connected by a link 28 with an arm 29 fixed on a rock-shaft 31 in the base frame. This rock-shaft in turn is connected by a connecting rod 32 with a crank pin 33 on a crank disc 34 fixed upon a shaft 35 mounted in bearings 36 (Fig. 6) in the base frame of the apparatus and continuously rotating, as will hereinafter be described.

Each feed slide 26 is provided with a feed shoulder 37 adapted to engage behind a pre-

sented can end 38 to advance it on to the support 23. The can end support 23 is mounted upon the upper end of an axially movable and rotatable shaft 39, which is positioned through a sleeve 41 having bearing 42 in a bushing 43 extending through the main frame at 43.

Preparatory to each lining operation, the can end support is adapted to be lifted by mechanism to be presently described into engagement with an upper clamping member 44 idly and freely rotatable about a shaft or sleeve 45 threadedly engaged at 46 in an arbor 47 extending up from the table 21 to which it is secured by a bolt 48, ball bearings 49 being provided if desired.

The upward movement of the can support with the can end carried by it is accomplished by a bellcrank lever 51 (Fig. 3) pivoted at 52 in a downwardly extending arm 53 beneath the table. One arm of this bellcrank is bifurcated at 54 and is provided with pins 55 engaging in a slot 56 formed in a collar 57 secured on the lower end of the shaft 39. The other arm of this bellcrank extends up into engagement with a pin 58 fast in a slide bar 59 mounted upon a slideway 61 beneath the bed. The bar 59 and the bellcrank 51 are pushed to lowered position by a spring 62 bearing against an end of the slide and an adjustable bolt 63 arranged through an upright 64 from the guideway 61. The purpose of the slide bar 59 is to lock certain parts against movement, except when such movement is desired. The bellcrank 51 is provided with a roller 65 which engages a cam 66 having a lifting dwell 67 for maintaining the can end support in lifting and clamping position throughout the predetermined desired period. A desired and predetermined rotation is imparted to the supported can end and clamp after the parts are in clamping relation, and this is accomplished by a Geneva movement to be now described, reference being had to Figs. 3, 6, and 9 to 12.

A shaft 71 is mounted in bearing 72 alongside shaft 35, and this shaft is provided with a beveled gear 73 which meshes with a beveled gear 74 on a shaft 75 arranged vertically in bearings 76 beneath the bed. The shaft 75 carries a gear 77 which meshes with a gear 78 keyed to shaft 39. The shaft 71 also is provided with a Geneva pinion 79 adapted for engagement with a Geneva segment 81 on shaft 35, or rather upon a sleeve 82 fixed on said shaft. This sleeve also has fast to it the Geneva disc 83, circular in form except that it is cut away throughout the arc of the segment 81. A rider 84 is mounted upon the hub 85 of the Geneva gear 79, and is adapted to ride upon the outer face of the Geneva disc to prevent rotation of the shaft 71, except when the Geneva segment is rotating the Geneva gear.

At each end of the arcuate portion of the disc 83, the corners 86 are cut away to facilitate the engagement of the grooved face 87, to permit the arcuate face of the rider 84 to readily engage and disengage the circumferential face of the Geneva disc.

In order to insure positive engagement of the tooth of the gear segment in accurate meshed relation, and also to insure accurate engagement of the gear of the Geneva rider with the Geneva disc, I fix a member 88 on the shaft 79, this member having arms 89 and 91. A companion member 92 is fixed upon the shaft 35 and at appropriate points two rollers 93 and 94 are arranged in the path of travel of the arms 89 and 91.

Fig. 11 shows the arrangement of the parts of the Geneva movement during the feeding of a can end on the can end support, and continued rotation of the shaft 35 causes the roller 93 to engage the arm 91 as the segment approaches the gear. The circumferential face of the Geneva disc is cut away slightly at 95 to permit this.

Fig. 9 shows the segment and gear in engagement, during which time a revolution and a half is imparted to the can end support.

Fig. 12 shows the arrangement of the parts at the end of the Geneva action, the roller 94 engaging back of the arm 89 and swinging the rider 84 positively into engagement with the circumferential face of the disc. The circumference is cut back at 96 to facilitate this; and

Fig. 10 shows the arrangement of the Geneva movement after the can end support has come to rest.

The can end nozzle, as has been described, causes the delivery of lining material to the flange of the can end throughout a full complete revolution of the end. Construction of this nozzle and attendant parts is perhaps best shown in Figs. 1, 4, and 5.

A tank 101 is mounted on the bed 21, and is provided with an outwardly extended hollow delivery arm 102 formed at its end remote from the tank into a bearing sleeve 103. A shaft 104 extends through this bearing and upon it is fixed a sleeve 105 of a nozzle support and conduit 106. The nozzle proper 107 is mounted in the outer end of the support 106. All of the parts are preferably arranged so that heat may be continuously applied to the compound material, and to this end the compound is contained within an inner chamber 108 in the tank and the passageway 109 through the arm 102 is jacketed at 111. A steam jacket 112 is or may be provided through the nozzle support 106 and about the passage 113. Communication between the passages 109 and 113 is formed by a simple bore 114 extending vertically through the shaft 104, enlarged openings 115 and 116 being provided

to establish communications with the passageways 109 and 113.

The nozzle is adapted to be swung about the center of the shaft 104 to follow the contour of the flange of can end. It is fast on the shaft 104, which is free to turn in the bearing 103. The movement of the nozzle with the flange of the can end is accomplished by a cam 117 mounted beneath the can support and fixed to the sleeve 41 at 118 thereof. The sleeve 41 turns with shaft 39 and the cam with it. This cam is provided with a groove 119 within which is engaged a cam roller 120 upon the end of an arm 121. The arm 121 is fast upon the lower end of the shaft 104, so that the shaft is rocked by the cam in accordance with the departures of the flange contour from a true circle. The opening 115 is sufficient to permit free communication between the passage 109 and the passage 114 throughout the range of rocking movement.

A manually operable valve 122 is provided in the bracket 102 and an automatic valve 123 is provided to open and close the nozzle 107 at the desired instants in the cycle of operation. The valve 123 consists of a valve rod adapted to open and close the passage 113, this passage when open communicating with the vertical delivery passage 124 to the nozzle. The valve rod 123 extends out through a sleeve housing 125 having bearing in a cap 126 at the top thereof, and is provided at its upper end with a head weight 130, which engages upon the top of an arm 127, the rod passing through an opening 128 therein. This weight and the weight of the rod normally hold the valve 123 in closed position, and this arrangement maintains until the can end support has received a can end and has started its rotation. If no can end is present upon the lifting of the can end support, the valve remains closed.

The mechanism for thus controlling the nozzle 123 will now be described: A vertically reciprocating rod 131 is mounted in a bearing 132 and passes through a sleeve 45, in which it also has bearing. At the lower end, this rod is provided with a can end detector head 133 located just above the can end support when in lower position. A recess 134 is provided in the top of the can end support and if no can end be present when the support is raised, the head 123 engages the bottom of the recess and is lifted with the support. If, however, a can end be present, the presented face of the can end engages the head 133 and the rod is lifted a correspondingly greater distance, sliding lengthwise in these lifting movements in its bearings. This head 133 is rotatably connected with the rod 131 at 140.

A bracket 135 is fixed to the rod by pins 136 and carries a lifter ledge 137 adapted to engage under a roll 138 provided on the end 130

of lever arm 127 by a shoulder bolt 139. This upward movement of the lever arm 127, when a can end is presented, is not sufficient to open the valve, arranging the valve, however, so that the passageway 113 is barely closed.

The ledge 137 (Fig. 8) is fast upon the upper end of a vertical slide rod 141 mounted in bearings 142 and 143 in the bracket 135, 10 the ledge member normally resting against the lower bearing 143. The slide rod is loosely pivoted at 144 to a lever 145 pivoted in turn at 146 to the bracket. The lever 145 is in turn engaged at 147 with a link 148 to 15 a bellcrank 149 pivoted at 151 adjacent the shaft 35.

The bellcrank 149 (Fig. 7) is provided with a roller 152 adapted to engage a continuously rotating cam 153 on shaft 35, 20 which cam has a nozzle opening dwell 154 adapted to engage the roller 152 and swing the bellcrank in a clockwise direction (viewing Fig. 7). This pulls downwardly on the link 148, swinging the lever 145 to further 25 raise the lifter ledge 137 and open the valve throughout the time that the dwell 154 is engaging the roller 152.

In order that the can support, and more particularly the cam 117 shall be in accurate 30 position to start a can lining operation, means are provided for locking the gear 78 against movement while the can end support is lowered. A collar 161 is fixed on the shaft 39 and this collar is provided with a recess 35 162 (Fig. 3) into which the slide bar 59, already described, engages at the end of each rotation of the can end support, and from which it is only withdrawn when the dwell 67 of cam 66 positively withdraws it preparatory to the starting of the next rotation. 40

Power is introduced into the machine from a power pulley 171 mounted upon a shaft 172 having bearing as at 173 in the frame. This power shaft 172 is provided with a 45 pinion 174 engaging a gear 175 on shaft 35. Shaft 172 also carries a beveled pinion 176 which meshes with a companion pinion 177 on a cross-shaft extending through bearing 178 in the frame and carrying at its opposite end a sprocket wheel 179, which sprocket wheel is employed to drive an agitator of any suitable type of construction in tank 101.

The gear 175 is yieldingly secured on shaft 35 (Fig. 6) in order that should the apparatus become jammed from any cause, the power may be disconnected from the operating and moving parts. A clutch collar 181 is slidable longitudinally of the shaft 35 and is pressed toward the gear by a spring 182 50 bearing against a spring holding collar 183 fast on one end of the shaft. The hub 184 of the gear 175 is provided with a clutch tooth 185 which normally engages in a companion recess 186 in the sliding collar 181.

60 After the can end has been lined and re-

turned to lower position, it is removed by the same feed bars 26 that positioned it upon the support. To this end forward lugs 191 are arranged on the feed bars and in position to engage behind the end and advance 70 it in the direction of feed after a lining operation. The timing of the apparatus is such that the lugs 191 return after a feeding operation back into operative position, while the can end previously fed is lifted 75 out of its return path of travel.

In delivering the can end from the can end support, it is carried by the feed bars on to a belt 192 which is trained over a drum 193 fixed on a shaft 194 having bearings at 80 195 in the frame. The shaft 194 is provided with a sprocket 196 connected by a sprocket chain 197 with the sprocket wheel 198 on shaft 35.

It will be manifest that the can ends of any desired shape can receive compound in the apparatus hereinbefore described, and this includes circular, rectangular, oval and ends of other shape. All that is necessary to the accomplishment of this result is the provision of a cam having a contour corresponding to the contour of the flange of the can end to be lined, and the provision also of a compound feeding cam 153 with the proper dwell 154 to determine the period of nozzle opening.

The parts may be readily separated to remove the cam 117 by swinging the nozzle about its shaft 104, and by swinging also the arbor 47 about the bolt 48. A holding latch comprising a pin 201 mounted in the armor is provided, and this pin is adapted to engage an opening 202 in the bed. The pin is spring pressed by a spring 203 into locking position and is adapted to be 100 lifted by finger piece 204 at its top.

If desired, weight roller 205 (Fig. 1) on pivoted arms 206 mounted in brackets 207 may be provided to bear on the ends as they are fed to the support, and a similar 110 roller 208 on arm 209 may be arranged to bear on the ends as they leave the lining station.

It is thought that the invention and many of its attendant advantages will be understood from the foregoing description, and it will be apparent that various changes may be made in the form, construction and arrangement of the parts without departing from the spirit and scope of the invention 115 or sacrificing all of its material advantages, the form hereinbefore described being merely a preferred embodiment thereof.

I claim:

1. In an apparatus for applying lining compound to the flanges of can ends adapted to be interfolded with flanged can bodies to form double seams, the combination of means for rotating the can ends about a predetermined axis, a lining nozzle above 120

said can end and movable towards and from said axis during the lining operation, and means acting during said operation for moving said nozzle in accordance with change of 5 the distance between successive flange portions to be lined and said axis.

2. In an apparatus for applying lining compound to the flanges of can ends adapted to be interfolded with flanged can bodies to 10 form double seams, the combination of means for rotating the can end about a predetermined axis, a nozzle and cam member movable with the can end, said cam having a groove coincident with the flange of a 15 can and being rotated, and connections between said nozzle and cam to cause said nozzle to follow the flange of the can end.

3. In an apparatus for applying lining compound to the flanges of can ends adapted 20 to be interfolded with flanged can bodies to form double seams, the combination of a can end and rotating device, a nozzle adapted for arrangement above the flange of a can end in said device and movable relative to 25 the can end, and means acting during the lining operation for moving said nozzle toward and from the axis of rotation of said end as the end rotates.

4. In an apparatus for applying lining 30 compound to the flanges of can ends adapted to be interfolded with flanged can bodies to form double seams, the combination of a device for supporting a can end and rotating it about a predetermined axis, a nozzle ar- 35 ranged above the flange of a can end, and means arrangeable below the can end and movable conjointly therewith for causing the nozzle to follow accurately the flange of a can end as the can is rotated.

40 5. In an apparatus for applying lining compound to the flanges of can ends adapted

to be interfolded with flanged can bodies to 45 deform double seams, the combination of a device for supporting and rotating the can end to be lined throughout a predetermined path in excess of a single revolution, a nozzle arranged above the presented flange of a can end supported in said device, means for causing the nozzle to follow accurately the 50 successively presented portions of said flange, and means limiting the period of delivery of compound from said nozzle to substantially a single revolution of said can end.

6. In an apparatus for applying lining 55 compound to the flanges of can ends adapted to be interfolded with flanged can bodies to form double seams, the combination of a device for supporting and rotating a can end, a nozzle arranged above the flange of a 60 supported can end, means for rotatably supporting said nozzle about an eccentric axis, and devices for causing said nozzle to be swung in accordance with the shape of the 65 can end to maintain the nozzle accurately above the presented flange.

7. In an apparatus for applying lining 70 compound to the flanges of can ends adapted to be interfolded with flanged can bodies to deform double seams, the combination of a device for supporting and rotating a can end to receive compound, a nozzle eccentrically swinging in accordance with the flange of the can end, means for so swinging the nozzle during the lining operation, a reservoir for containing lining compound, a connection between said reservoir and said nozzle, and means maintaining a predetermined temperature of said compound in said 75 tank and from said tank to said nozzle.

RONALD E. J. NORDQUIST.
